UNITED STATES PATENT OFFICE

2,029,056

ROTARY SPREADER

George E. Carlson, Chicago, Ill., assignor to Carlson Research Corporation, Chicago, Ill., a corporation of Illinois

Application December 1, 1933, Serial No. 700,382

7 Claims. (Cl. 91—67.4)

This invention relates to receptacles for materials of a pasty consistency, such as shaving cream or cold cream, and it is particularly concerned with providing such receptacles with means for spreading the pasty material as it is discharged from the receptacle. It consists of certain features and elements of construction herein shown and described, as indicated by the claims.

10 In the drawings:

Figure 1 is a top plan view, and Figure 2 is a side elevation of a collapsible tube fitted with a special terminal at its discharge end, including a roller for distributing the contents of the tube in accordance with this invention.

Figure 3 is a vertical detail section taken as indicated at line 3—3 on Figure 2.

Figure 4 is a transverse section showing the terminal device of Figure 2 fitted to a different tube by means of an adapter.

Figure 5 is a section similar to Figure 3, but showing a modified form of spreading roller.

Figure 6 illustrates a further modification, being a section taken similarly to Figures 3 and 5, and showing a mounting for the distributing roller formed as an integral part of the tube or receptacle.

Figure 7 is also a vertical detail section showing another modification in which the distributing roller is mounted to rotate on an axis coincident with that of the discharge orifice of the tube.

The structure shown in Figures 1, 2 and 3 comprises a receptacle for such material as shaving soap or cream or cold cream, shown in the form of a metallic collapsible tube, 1, having the usual threaded neck, 2, with a discharge orifice extending therethrough. The orifice in the neck itself may be understood as of circular cross-section. Instead of the usual closure cap this invention provides a terminal fitting, 3, threaded to fit the neck, 2, and formed with a conical counter-bore in its lower end at 4 to seat against the conical upper end, 5, of the tube, 1.

45 The upper portion of the fitting, 3, provides upstanding ears, 6, which support a pin, 7, on which is journaled the spreader roller, 8, whose function is to distribute the contents of the tube, as desired. Between the roller, 8, and the end 50 of the tube neck, 2, the fitting, 3, is formed with an orifice, 9, preferably oblong in cross-section, whose longer dimension extends parallel to the axis of the roller, 8, so that the paste or cream discharged from the neck of the tube will be applied directly to a substantial portion of the

length of the roller. Preferably, the roller is formed with depressions or grooves, seen at 10 in Figure 3, and the material discharged from the tube is picked up by these grooves as the roller turns past the discharge slot, 9.

5 Rotation of the roller is, of course, produced by causing it to traverse the face or other portion of the body upon which the contents of the tube, 1, is to be spread. The roller shown in Figures 1, 2 and 3 is considered of suitable form 10 for spreading shaving cream over the cheeks and chin. It is of generally cylindrical form, with a slightly bulging contour. Figure 5 illustrates a roller, 17, intended for spreading cream or similar material, and for this purpose it is made 15 shorter than the roller of Figures 1 to 3, and more bulging, that is, more nearly approaching a spherical form, so that it will fit into the angles and recesses of the facial contour more conveniently. The roller, 17, is also made somewhat 20 shorter than the roller, 8, and for this reason the contour of its supporting fitting, 18, differs slightly from that of the fitting, 3. If desired, the sides of the fitting, 18, may be substantially 25 parallel, giving it a cylindrical form, so that a protective dust-cap, 19, may be slipped over it to enclose the roller, 17, and will be frictionally retained on the fitting.

Figure 4 shows a tube, 11, having a smaller threaded neck, 12, than that of the tube, 1, and for 30 securing the fitting, 3, to such a tube, there is provided an adapter, 13, having a neck portion, 14, which is internally threaded to fit the neck, 12, and externally threaded to fit the threaded bore of the part, 3. The adapter also includes 35 a conical flange portion, 15, which fits snugly against the counter-bore, 4, of the fitting, 3, and rests upon the conical end wall, 16, of the tube, 11. Figure 6 illustrates a modification of the invention in which the collapsible tube or container, 20, includes a specially formed end wall, 21, provided with upstanding ears or lugs, 22, which support a pin, 23, on which a spreader roller, 24, is journaled. Thus the supporting fitting for the roller is made integral with the 45 receptacle. The roller, 24, may be of any suitable form, depending on the use to which the material in the tube, 20, is to be put, and may be externally grooved, either as shown in the preceding figures, or with obliquely arranged recesses, as seen at 25 in Figure 6. The discharge orifice, 26, in the end wall, 21, leads directly to the roller, 24, and may be either circular or oblong in cross-section. If desired, the tube may be provided with a dust cap, 27, which is shown as 50 55

fitting snugly over the cylindrical body of the tube, and completely enclosing the terminal, 21, and the roller, 24, carried thereby.

In Figure 7 the spreading roller, 30, is shown as being disposed with its axis aligned with the axis of the bore, 31, in the threaded discharge neck, 32, of the tube, 33. A terminal block or fitting, 34, is screwed onto the neck, 32, and clamps against the end of said neck the flange, 35, of a bushing, 36, which projects from the upper end of the block, 34, and serves as one bearing on which the hollow roller, 30, rotates. The other end of the roller is provided with a trunnion, 37, and a bail, 38, supported on the block, 34, provides a bearing, 39, for said trunnion. The block, 34, is notched at diametrically opposite points to receive the lower ends of the bail, 38, so that the outwardly turned foot-pieces, 40, of the bail, may be clamped under a securing ring, 41, screwed onto the upper end of the block, 34. This forms a convenient mode of assembly, and permits the device to be taken apart readily if it is desired to cleanse the interior of the hollow spreading roller, 30. The surface of the roller is perforated, as seen at 42, for discharging the cream or paste which reaches the cavity of the roller through the outlet, 31, and the bushing, 36.

While there are shown and described herein in certain specific structures embodying the invention, it will be manifest to those skilled in the art that further modifications and re-arrangements of the parts may be made without departing from the spirit and the scope of the invention, and that the same is not limited to the particular forms herein shown and described, except in so far as indicated by the appended claims.

I claim:

- 40 1. A spreader including a receptacle having a discharge orifice, a roller mounted for rotation adjacent the orifice to receive material on its surface, and a support in which the roller is mounted having cheeks closely fitting against the ends of the roller with curved surfaces surrounding the orifice and adjoining said cheeks, said surfaces conforming closely to the curved side portions of the roller between its ends and the area exposed to the orifice.
- 45 2. A spreader including a receptacle, a support associated therewith and a roller mounted for rotation in the support, the support having an orifice leading from the interior of the receptacle to the surface of the roller, and having curved surfaces surrounding the orifice and conforming closely to the curved contour of the roller adjacent the area exposed to the orifice.
- 50 3. A spreader including a receptacle having a threaded neck, a support formed with an orifice extending through it and threaded at one end to engage the threaded neck of the receptacle,

and a roller mounted for rotation in the support closing the orifice whereby the support with its roller serves as a cap for the receptacle, said support having curved surfaces adjoining the orifice and conforming closely to the curved contour of the roller adjacent the area which closes the orifice. 5

4. In combination, a collapsible tube for material of pasty consistency and provided with a discharge orifice, a support at the orifice and a roller mounted for rotation in the support with a portion of its area exposed to the orifice serving as a closure therefor, the support having curved surfaces adjoining the orifice and conforming closely to the curved contour of the roller beyond its area exposed to the orifice, whereby the material may be fed to the surface of the roller by collapse of the tube and distributed from the roller by rotation of the latter. 10

5. A spreader including a receptacle, a support associated therewith and a roller mounted for rotation in the support, said support having an orifice leading from the interior of the receptacle to the surface of the roller, said roller having a plurality of depressions in its surface 25 spaced apart circumferentially, and the support having curved surfaces conforming closely to the curved contour of the roller and extending from both sides of the orifice circumferentially by more than the width of one depression. 30

6. A spreader including a receptacle, a support associated therewith and a roller mounted for rotation in the support, said support having an orifice leading from the interior of the receptacle to the surface of the roller, said roller having longitudinally extending grooves terminating inwardly from its ends, and the support having curved surfaces surrounding the orifice and conforming closely to the curved contour of the roller between its ends and the ends of the grooves 40. 35 whereby the roller serves as a closure for the orifice.

7. A spreader including a receptacle, a support associated therewith and a roller mounted for rotation in the support, said support having an orifice leading from the interior of the receptacle to the surface of the roller, said roller having longitudinally extending grooves terminating inwardly from its ends and spaced apart circumferentially, and the support having cheeks closely fitting against the ends of the roller with curved surfaces adjoining said cheeks conforming closely to the curved end portions of the roller between its ends and the ends of the grooves, said curved surfaces extending circumferentially at both sides 55 of the orifice by more than the width of one groove whereby the roller serves as a closure for the orifice and the grooves act to receive material from the orifice for distributing it when the roller is rotated. 60

GEORGE E. CARLSON.
